FIRE ALARM BOX.

No. 443,182.

Patented Dec. 23, 1890.

UNITED STATES PATENT OFFICE.

JOHN J. RUDDICK, OF OMAHA, NEBRASKA, ASSIGNOR TO THE INTERSTATE FIRE ALARM COMPANY, OF SAME PLACE.

FIRE-ALARM BOX.

SPECIFICATION forming part of Letters Patent No. 443,182, dated December 23, 1890.

Application filed September 13, 1890. Serial No. 364,830. (No model.)

To all whom it may concern:

Be it known that I, JOHN J. RUDDICK, a citizen of the United States, residing at Omaha, in the county of Douglas and State of Nebraska, have invented a new and useful Improvement in Fire-Alarm Boxes, of which the following is a specification.

My present invention relates to fire-alarm boxes, and its object is to improve the construction of certain details of boxes of the general class shown in my patent, No. 404,438, dated June 4, 1889.

The invention consists in the construction substantially as hereinafter described and claimed.

Like letters refer to similar parts in the several figures of the drawings, in which—

Figure 1 is a plan view of a fire-alarm containing my improvement. Fig. 2 is a vertical section of the same. Fig. 3 is a top view of certain portions of the mechanism shown in Fig. 1. Fig. 4 is a side view of the same. Fig. 5 is a detail view, in side elevation and partly in section, of the starting and winding lever and its connection with the main shaft. Fig. 6 is a section of the same on the line xx , looking upward. Fig. 7 is a detailed view of the sleeves.

Inasmuch as my present invention relates entirely to improvements in a few details of the mechanism illustrated and set forth in my former patent, I shall not attempt in this specification to set forth in detail the other features of the apparatus with which the present invention is designed to be connected, but will merely generally indicate the same.

A designates the box, of the usual construction, which contains a clock mechanism, a magnet, and the other general features of boxes of this class. The number-wheel in this box carries another wheel B, provided with a vertical peripheral flange cut away at intervals corresponding to the teeth or pins of the number-wheel, as has heretofore been done. Upon the upper surface of the outer rim of this wheel B, I place a plate C, as has before been done; but instead of the spring which was employed in my former patent to direct the detent-pin outwardly, I in the present instance raise from the top surface of the plate C a cam D, which is curved so as to di-

rect the detent-pin outwardly just as the spring did in my previous patent. This cam may be formed integrally with the plate C, or may be affixed thereto in any suitable manner, and I find in practice that it is preferable to the spring heretofore used for a similar purpose. The detent-pin is arranged and located as heretofore and connected with a pivoted detent-lever F, the outer end of which is forced upward by a spring and has a projecting vertical piece for contact with the releasing power or other actuating power.

The main shaft G of the clock-work extends upwardly through the casing or cover of the box. Rigidly secured to this main shaft is a ratchet H, into a tooth of which a pawl I is normally held by means of a spring or otherwise.

A disk K, carrying a hub or sleeve, loosely surrounds the shaft, and the winding and releasing lever L also carries a hub or sleeve and is mounted to revolve loosely upon the same shaft. In the present instance I provide the sleeve of the disk with a reduced portion for a part of its length, and form a groove in the lower larger portion thereof, in which a tongue upon the sleeve of the lever may freely play and move a distance determined by the throw which it is desired the lever shall have. I place a spring M between the disk and the lever and connect the opposite ends thereof to these parts. In the present instance I have shown a coiled spiral spring; but I find a flat spring to be efficient. One end of the lever L may have a handle for operating the same, and the other end a toe or cam piece N.

The operation of my invention is as follows: When it is desired to release the clock mechanism the detent-pin is lifted above the stop on the flanged wheel by turning the lever L until its toe or cam-piece N moves over and comes in contact with the vertical projection from the detent-lever and thereby depresses the same. By the same movement of the lever L the spring M secured thereto is caused to move, and by its stress to tend to turn the disk carrying the pawl I, and thus turn the ratchet H, and the shaft to which such ratchet is affixed, and wind up the mainspring of the clock-work. If, however, the mainspring has already been wound, the lever may be still

moved for the purpose of operating the projection and releasing the detent-pin, inasmuch as the groove in the hub of the disk permits the tongue of the hub or sleeve of the lever to move sufficiently to give a complete throw to the lever, and the spring will merely be tightened during this movement. If the main-spring of the clock-work has been partially wound up, the throw of the lever will put its spring under strain or tension and thus cause the disk to move and complete the winding of the mainspring, and then the tongue will move in the groove until the throw of the lever is completed. In this manner a single throw of the lever can be made to wind the clock mechanism and simultaneously release the detent-pin, so that such mechanism may act to give the alarm, and, on the other hand, if the clock mechanism has been wound and it is desired to sound an alarm, the spring-connection between the lever and the shaft and the play allowed by the tongue and groove will permit the lever to be given its full throw and thus release the detent-pin independently of the winding mechanism.

It is obvious that my improvements may be applied to alarm-boxes varying in some particulars from that shown in my former patent, though I prefer to use such box or boxes substantially similar thereto. It is also manifest that in place of the two sleeves and the tongue-and-groove connection between them, any construction which would connect the shaft and the winding and releasing lever so as to provide for some play between the same would be an equivalent to the construction heretofore described for this purpose and would come within the spirit of my invention. A skilled mechanic could readily devise many different forms of construction for this purpose.

What I claim, and desire to secure by Letters Patent, is—

1. In a fire-alarm mechanism, the combination of a clock mechanism, a single lever connected to the clock mechanism for winding the same, and a detent for the clock mechanism arranged in the path of the clock-winding lever, whereby the movement of the latter may directly accomplish the double function of winding the clock mechanism and releasing the detent.

2. In a fire-alarm mechanism, the combination of a clock mechanism and a detent therefor with a mechanism for winding the clock mechanism and releasing the detent, said mechanism having provision for permitting a play between it and the clock mechanism when the latter is wound and it is desired to operate the detent, substantially as shown and described.

3. In a fire-alarm mechanism, the combination, with a clock mechanism, of a detent therefor, a lever yieldingly connected to the

main shaft of the clock mechanism and having a projecting portion which may be brought over and in contact with the detent to release the same, whereby the detent may be released and the clock mechanism wound simultaneously or the detent released separately and after the clock mechanism has been previously wound, substantially as described.

4. In a fire-alarm mechanism, the combination, with a clock mechanism, of a detent therefor and a lever loosely mounted upon the main shaft of the clock mechanism and having a yielding connection therewith, and having a projecting portion for operating and releasing the detent, substantially as and for the purpose set forth.

5. In a fire-alarm, the combination, with a clock mechanism, of a detent therefor, the main or winding shaft of such clock mechanism extending through the cover, and a lever loosely mounted upon the outer end of such main shaft and yieldingly connected therewith, and having a projecting end for operating and releasing the detent, substantially as and for the purpose set forth.

6. In a fire-alarm mechanism, the combination of a clock mechanism provided with a main shaft extending through the cover of the same, a ratchet affixed to such shaft, a disk having a pawl for engaging such ratchet, and a hub or sleeve having a groove therein, a lever loosely mounted upon the shaft and having a hub provided with a tongue having a free play in such groove, a spring whose respective ends are connected to the lever and the disk, a projecting portion to the lever, and a detent for the clock mechanism adapted to be released by such lever, substantially as and for the purpose set forth.

7. In a fire-alarm, the combination, with a flanged wheel provided with a definite number of breaks in such flanges, a plate upon the upper face of such wheel having a hook projecting outwardly beyond the flange of the same, a rigid cam attached to the plate and having its surface incline toward and beyond the point of the hook, of a detent-pin normally held upon one side or the other of the flange to the wheel and adapted to be guided by the cam from the inside of the flange to the outside thereof, substantially as shown and described.

8. In a fire-alarm, the combination of the known form of flanged wheel having the detent-hook, a rigid cam-face affixed to such hook and inclined toward and beyond the point thereof, and a detent-pin for co-operation with said parts, substantially as shown and described.

JOHN J. RUDDICK.
